(57) **CLAIM**

The ornamental design for a table saw, as shown and described.

DESCRIPTION

FIG. 1 is a front perspective view of a table saw showing our new design;

FIG. 2 is a right side perspective view thereof;

FIG. 3 is a rear perspective view thereof;

FIG. 4 is a left side perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken lines shown in the drawings illustrate portions of the table saw that form no part of the claimed design.
